(57) CLAIM

We claim the ornamental design for a disc toy, as shown and described.

DESCRIPTION

FIG. 1 is a perspective view of a front side of the disc toy showing our design;

FIG. 2 is a perspective view thereof;

FIG. 3 is a front view thereof;

FIG. 4 is a right-side view thereof;

FIG. 5 is a left-side view thereof; and,

FIG. 6 is a bottom view thereof.

The broken lines in the figures form no part of the claimed design.
